UNITED STATES PATENT OFFICE.

CHRISTIAN F. BAEHR, OF CLEVELAND, OHIO, ASSIGNOR TO THE VAN DORN ELECTRIC TOOL COMPANY, OF CLEVELAND, OHIO, A CORPORATION OF OHIO.

GLUE POT.

Application filed February 23, 1923. Serial No. 620,741.

To all whom it may concern:

Be it known that I, CHRISTIAN F. BAEHR, a citizen of the United States, residing at Cleveland, in the county of Cuyahoga and 5 State of Ohio, have invented certain new and useful Improvements in Glue Pots, of which the following is a specification.

This invention relates to glue pots and more particularly, to a portable glue pot 10 structure comprising an outer, water containing vessel, a glue containing vessel removably mounted therein, and means for heating the glue.

One disadvantage of such prior glue pot 15 structures is the arrangement of the heating means, which is seldom held in heat conducting engagement with the bottom of the outer vessel, so that maximum heating effects are not obtained and the glue is not 20 uniformly heated. In some glue pot structures, in which electrical means is employed to heat the glue, a thermostatic control is provided for maintaining the glue at the proper temperature, say between 140° and 25 150° Fahrenheit. In some instances, means is also provided for regulating the sensitivity of the thermostatic control, the regulating means being located outside of the 30 structure, usually at a point remote from the thermostatic control. Assembly of these prior structures has, therefore, been extremely difficult, and due to the difficult 35 access to the heating means and the thermostatic control, inspection and repair of these parts are inconvenient and expensive.

It is therefore the object of the present 40 invention to improve the arrangement of the heating element by the provision of a detachable base for the outer vessel, said base having a yielding crowned portion 45 which forces the heating element into firm and uniform heat conducting engagement with the bottom of the outer vessel. Furthermore, by merely detaching the base, the heating element is readily accessible for inspection or repair.

A further object of the invention is to 50 improve the arrangement of the thermostatic control and the regulating means therefor by arranging said devices in a diametrically extending channel in the bottom and within the confines of the outer vessel, so that the thermostatic control is

fully responsive to variations in temperature of the liquid in said vessel. Moreover, both the thermostatic control and the regulating means therefor are closely associated at the parting of the outer vessel and the base so that separation at this point renders both of said devices readily accessible for inspection or repair. This arrangement also assists materially in the assembly of the heating element and the control and regulating devices in the structure.

Further objects of the invention are in part obvious and in part will appear more in detail hereinafter.

In the drawings, which represent one suitable embodiment of my invention, Fig. 1 is a front elevation, parts being broken away to expose interior parts; Fig. 2 is a plan view of the outer vessel or container; Figs. 3 and 4 are vertical sectional views thereof, taken at right angles to each other; Fig. 5 is a bottom plan view of the outer vessel; Fig. 6 is a vertical sectional view of the removable base; Fig. 7 is a plan view thereof; Fig. 8 is a plan view of the heating element, parts being broken away for clearness of illustration; Fig. 9 is an edge view thereof; and Figs. 10 and 11 are detail views showing modified seating arrangements at the junction of the outer vessel and base.

Referring to the drawings, 1 represents the outer, water containing vessel or container having the usual chamber 2, which vessel may be of any suitable material, such as cast iron, and of any suitable shape, being here shown as frusto-conical. The vessel is provided in its bottom with a diametrically disposed, upwardly extending channel shaped portion 3, open at the bottom of the vessel and closed at each end by the side wall thereof, as indicated in Fig. 3. The bottom of said vessel is therefore divided into two substantially semi-circular heating element engaging portions 4 with a diametrically disposed channel or recess 5 separating them, in which channel is suitably secured the thermostatic control later to be described.

Said vessel is supported on a detachable base, comprising a resilient convex or crowned grid portion 6, an upwardly ex-

tending circumferential flange 7 within which the annularly recessed bottom of the outer vessel seats, and a depending, annular skirt portion 8 having circumferentially spaced feet portions 9 at its lower end, as indicated in Fig. 6. When the outer vessel is seated upon the flange 7, sufficient space is provided between the separated bottom portions 4 and the crowned grid portion 6 for the heating element, which is adapted to be yieldingly and uniformly held in heat conducting engagement with said bottom portions 4, as will later appear. The base is firmly but detachably secured to the outer vessel by screws 11 passing through the marginal portion of the grid 6 and secured in circumferentially spaced lugs or bosses 12 formed in the bottom of said outer vessel. The skirt portion 8 of the base is preferably closed at the bottom by a circular protector plate 13, secured to lugs 14 on the inner sides of the feet 9, the plate providing a dead air heat insulating chamber 15 within the skirt portion.

25 The inner, glue containing vessel 16 is preferably made of aluminum, and also frusto-conical in shape to correspond to the outer vessel 1. This inner vessel is of such size that when it is secured within the outer vessel, as shown in Fig. 1, sufficient space is provided between the vessels, both at the side and bottom, for the circulation of the water, indicated at 17, by means of which heat is transferred from the heating element to the glue within chamber 18, as is usual.

40 The means for removably securing the inner vessel within the outer vessel comprise interlocking lugs on the upper, adjacent side wall portions of the two vessels, said lugs constituting the well known bayonet lock connections, and an annular, integral flange 19, extending outwardly and downwardly from the upper edge of the inner vessel and engaging and extending well beyond the upper end of the side wall of the outer vessel, as indicated in Fig. 1.

45 To securely hold the inner vessel against tilting movement, three sets of lugs are preferably provided, each set comprising a horizontal, circumferentially extending lug 20 on the upper, inner wall surface of the outer vessel, and a similarly extending lug 21 engaging therewith, each lug 21 being arranged on the lower end portion of a longitudinally extending vertical web member 22 on the upper, outer wall surface of the inner vessel. To limit relative rotary movement of the two vessels, each lug 20 is provided with a depending stop portion 20^a, which will be engaged by the ends of lugs 21, as will be readily understood.

50 By the provision of the integral flange 19 for covering the space between the two vessels, all cracks or crevices through which

the glue might seep are avoided, and by extending the flange downwardly and well beyond the side wall of the outer vessel, any glue which drips or splashes onto this flange will readily drain therefrom and fall beyond the structure. 70

55 Flange 19 is provided at its upper edge, at diametrically opposed points, with upwardly extending, integral ears 23 having suitable apertures for receiving a bail or handle member 24, by means of which the glue pot structure may be readily carried. In the preferred embodiment of the invention, a portion of the handle is extended diametrically across the top of the inner vessel, as indicated in Fig. 1, to form a brush wiper 25 for removing excess glue from the brush. By securing the handle to the inner vessel in the manner shown, either the entire structure, or the inner vessel alone, 80 may be readily carried.

60 The heating element is in two parts, each substantially corresponding in size and configuration to the semi-circular bottom portions 4 of the outer vessel, and when properly arranged in the structure, underlie these portions and are therefore separated by an intervening space underlying the channel 5. Each part comprises a core 26, of any insulating material, such as mica, and provided at its edges with opposed notches or recesses 27 for receiving the turns of a resistance wire 28 wound therearound, as indicated in Fig. 8. The intervening spaces 29 between notches serve to insulate each 100 stretch of wire from its adjacent stretches, the entire core of each part being insulated by inserting the same between two correspondingly shaped sheets of mica 30. The two parts of the heating element thus formed rest upon a substantially circular layer of asbestos 31, which in turn rests upon and overlies the resilient, crowned grid portion 6 of the base. As before mentioned, sufficient space is provided for the heating element between said grid portion and the separated bottom portions 4 of the outer vessel, when the crown of said grid portion is flattened, which flattening results from the uniting of the base and the outer vessel. The heating element is therefore yieldingly and uniformly pressed into and held in heat conducting engagement with the bottom of the outer vessel, so that maximum 110 heating effects are obtained. 115

65 Suitably connected in the electric circuit with the two parts of the heating element is a thermostatic control for automatically maintaining the glue at the proper temperature, said control being arranged in channel 5, as before mentioned. The thermostatic control here shown comprises upper and lower contact members 32, 33, each having one end horizontally arranged upon the opposite faces of an insulating block 34, se- 120 125 130

cured by screws 35 to the lower face of a lug 36 depending from the middle of the channel shaped portion 3. Each of these contact members is provided at its free end with a suitable contact 37, arranged to co-operate with each other in making and breaking the electric circuit. The upper contact member 32 is a bimetallic member fully responsive to the heat condition at the bottom of the outer vessel, so that the contact 37 of this member will be automatically raised and lowered, as the temperature of the water 17 rises and falls, thereby opening or closing the electric circuit through the heating element.

Suitable means is provided for varying the distance through which the upper contact 37 must be moved to make or break the electric circuit, the means here shown comprising a rotatable adjustable member 38 of screw form. The head 38^a thereof is supported in an opening 39 in the side wall of the outer vessel, near the line of attachment of said vessel and the removable base, said head being readily accessible in said opening from outside the structure. The shank or body portion of said screw extends inwardly into channel 5, being suitably supported therein by a lug 40 depending from and extending across said channel, as indicated in Fig. 1. The inner tapered end 38^b of the screw is adapted to engage the beveled front end of an insulating block 41 suitably secured to the bottom face of the lower contact member 33. By turning the head 38^a of this regulating screw, the lower contact member 33 may be raised or lowered, thereby varying the distance through which the contact 37 of the upper contact member 32 must be moved to make or break the electric circuit.

By thus arranging the thermostatic control and the regulating member therefor within channel 5 and adjacent the line of attachment of the outer vessel and the removable base, the entire structure may be easily and quickly assembled, and inspection or repair of these parts readily and conveniently made.

In the preferred embodiment of the invention, a pilot lamp 42 is included in the electric circuit, which will, of course, be illuminated when the current is on. In the present illustration, said lamp is mounted in the skirt portion 8 of the removable base, as indicated in Fig. 1. A suitable cable or cord 43 for supplying current to the device also passes through said skirt portion, as indicated.

Any suitable wiring may be employed in connecting the heating element and the thermostatic control in the circuit, and since the wiring forms no special part of the invention, it is sufficient to say that any wiring arrangement may be employed, it only being

necessary to be sure that the thermostatic control can make and break the electric circuit including the heating element.

In the preferred embodiment of my invention, suitable means is provided at the junction of the outer vessel and the removable base for preventing creeping of the glue, such as by gravitation or the like, into the space between said vessel and base and onto the heating element arranged therebetween. In Figs. 10 and 11, the outer vessel and base are provided with interengaging flanges, with the flange of the outer vessel outside of the flange of the base and extending below the top of the same. While the flange of the outer vessel is here shown as extending within the periphery of the base, it might obviously be formed as extending outside thereof and below the top of the base, whereby sloppage of glue would be directed past the junction of the outer vessel and base. In Fig. 11, the bottom or lower face of the flange of the outer vessel, which is formed by an annular recess, is in the plane of the bottom of the vessel, so that said bottom may be machined in constructing said vessel, the construction thereof being thereby materially facilitated.

Suitable means is also provided in the preferred embodiment of my invention for effectively preventing the escape of steam or water from the space or chamber between the inner and outer vessels. The means here shown comprises an annular ring or flange 19^a depending from the lower face of the shedding flange 19 of the inner vessel and located adjacent the side wall of the outer vessel. As shown, flange 19^a is formed integral with flange 19 and the web members 22 of the inner vessel. As indicated in Fig. 1, flange 19^a extends below the upper edge of the side wall of the outer vessel, which is the point of engagement of vessel 1 and outwardly extending flange 19, so that steam rising to the top of the space or chamber between the two vessels, or water splashing to this point, is directed down past said point of engagement and is, therefore, effectively prevented from escaping.

Having described my invention, I claim:

1. A glue pot structure, comprising a container, a heating element, and a detachable base for supporting said container and said heating element, said base being provided with means for yieldingly pressing said heating element into heat conducting engagement with the bottom of said container.

2. A glue pot structure, comprising a container, a heating element, and a detachable base for supporting said container and said heating element, a portion of said base being so formed as to yieldingly and uniformly press said heating element into heat conducting engagement with the bottom of said container.

3. A glue pot structure, comprising a container, a heating element, and a detachable base for supporting said container and said heating element; a portion of said base being crowned so as to yieldingly and uniformly press said heating element into heat conducting engagement with the bottom of said container.
4. A glue pot structure, comprising a container, a heating element, and a detachable base for supporting said container and said heating element, said base being cast in one piece and including a crowned portion for yieldingly and uniformly pressing said heating element into heat transferring relation with the bottom of said container.
5. A glue pot structure, comprising a container having a diametrically disposed channel extending upwardly into the container and separating the bottom thereof into two substantially semi-circular heating element engaging portions, a base adapted to be secured to the bottom of said container, a heating element comprising, two parts, one for each separated bottom portion of the container, said heating element parts being held against their corresponding container bottom portions by said base, and a controller for said heating element arranged in said channel.
6. A glue pot structure, comprising a container, a base removably secured thereto, a heating element, a thermostatic control located between said container and said base, and regulating means for said thermostatic control accessible from a point outside the side wall of said structure and adjacent the line of separation of said container and said base.
7. A glue pot structure, comprising a container, a base removably secured thereto, a heating element, a thermostatic control located between said container and said base, and regulating means for said thermostatic control accessible from the outside at a point adjacent the line of separation of said container and said base, and terminating within the periphery of said container.
8. A heating device, comprising a container, a base removably secured thereto, said container and base parting in substantially the plane of the bottom of the container, said container and base having chambers adjacent their junction, a heating element arranged in one of said chambers, and a controller and regulator in other of said chambers, whereby said heating element and said controller and regulator are accessible when said container and said base are separated.
9. A heating device, comprising a container, a base removably secured thereto, said container and base parting in substantially the plane of the bottom of the container, said container being provided with a channel and said base being provided with a heating element chamber, both said channel and said chamber being adjacent the junction of said container and base, a heating element arranged in the chamber of said base, and a controller arranged in said channel.
10. A heating device, comprising a container, a base removably secured thereto, said container and base parting in substantially the plane of the bottom of the container, said container being provided with a channel and said base being provided with a heating element chamber, both said channel and said chamber being adjacent the junction of said container and base, a heating element arranged in the chamber of said base, and a controller and a regulator arranged in said channel, whereby said heating element and said controller and said regulator are accessible when said container and said base are separated.

In testimony whereof I hereby affix my signature.

CHRISTIAN F. BAEHR.
